UNITED STATES PATENT OFFICE

2,536,463

TOGGLE-ACTUATED SLIDING-JAW WRENCH

William C. Ratliff, Dallas, Tex.

Application March 18, 1946, Serial No. 655,167

3 Claims. (Cl. 81—126)

1

This invention relates to utility wrenches and more specifically to the type of wrench used in gripping and turning objects of cylindrical or polygonal design.

The principal object of the invention is to provide a wrench having jaws capable of applying and maintaining a sufficiently secure grip upon objects of a cylindrical or polygonal design without undue disfigurement of the surface of such objects while imparting rotational movement thereto.

Another object of the invention is to provide a wrench constructed in such a manner as to be equally effective upon objects adaptable to rotational movement irrespective of the shape of the object.

Still another object of the invention is to provide a tool so designed as to permit its effective use in close quarters.

A further object of the invention is to provide a portable vice or clamp, adaptable for use upon objects within its capacity.

A still further object of the invention is to provide a means of locking the device at a point capable of maintaining the pressure required to hold an object firmly within its jaws.

Still further objects and certain novel features of construction will become increasingly apparent as the description proceeds, considered in connection with the accompanying drawings wherein:

Figure 1 is a perspective view of an assembled wrench, shown partly in section to illustrate the relative positions of its various parts.

Figure 2 is a side elevational view of an assembled wrench, constructed according to the invention.

Figure 3 is a fragmentary side elevational view, shown partly in section to illustrate the inner construction details of the most essential parts, and

Figure 4 is a transverse sectional view corresponding to section 4—4 on Figure 2.

Continuing with a more detailed description of the drawings, and referring specifically to Figures 1 and 2, a means of leverage, hereinafter known as a handle 10, is provided, and is bored to receive a pivotal pin 11 which in turn is receivable in a housing 12 as shown.

The end of the handle 10 which is encased within the housing 12 is so designed as to provide a semi-circular shoulder on each side of a protuberance 13 in order to exert longitudinal pressure against side link plates 14. These links are eccentrically mounted on the protuberance 13, as

2

shown in Figure 3, by means of a countersunk pin or rivet 15. The opposite ends of the links 14 are similarly mounted on an extended portion 16 of a jaw 17 except that in this instance a countersunk pin or rivet 18 is concentric with the semi-circular arc of the end of the links 14 as shown in Figure 3.

A jaw 19 capable of parallel engagement with the jaw 17 is provided with a unitary extension 20 adaptable to slidable longitudinal movement within the housing 12. The extension 20 is bored and threaded to receive a threaded adjusting bolt 21 as shown in Figure 3. A knurled adjusting head 22, being an extension of the bolt 21, provides a means of imparting rotational movement to the latter and thereby permitting adjustable longitudinal movement of the extension 20 within the housing 12 thus affording a means of adjusting the capacity of the jaws 17 and 19.

20 The housing 12 is die-formed and is placed in position after the internal elements have been assembled. The abutting edges of the housing 12 are welded together thus forming a continuously enclosing shell for the movable parts therein. A depression 23 in the housing 12, having an aperture 24 permits the adjusting head 22 to be manually rotated as illustrated in Figure 4.

Referring now to Figure 3, the dotted lines represent the position of the handle 10 when maximum pressure has been applied at any adjustment of the jaw capacity. In this position a bore 25 in the handle 10 is aligned with a perforation 26 in the housing 12, thus permitting the insertion of a pin or key (not shown) through the housing 12 and the handle 10, thereby locking the lever mechanism of the wrench so that it may be used on square objects where no pressure is required for holding the work firmly.

Upon releasing the pressure exerted upon the handle 10 into the position shown in Figure 3, the pivotal action upon the pin 11 causes the enclosed end of the handle 10 to move laterally outward through an opening 27 in the housing 12. This action is transmitted to the links 14 by the mutually interlocking pin 15, causing a longitudinal pull to be exerted upon the interlocking pin 18, which action, in turn, compels longitudinal movement on the part of the jaw 17, thereby increasing the capacity of the jaws 17 and 19 to release an object held therein. A shoulder 28 is provided on the jaw 17 adaptable for abutting engagement on an edge of the housing forming a stop 29 in order to halt the longitudinal movement of the jaw 17 extension within the housing 12. Similarly, and acting in coincidence there-

with, a notch or shoulder 30 in the outer edges of the links 14 are adaptable to abutting engagement with a stop 31 of the housing 12. In like manner a notch or shoulder 32 is adaptable to similar engagement with a stop 33 of the housing 12. For further security a notch or shoulder 34 is adaptable to meet in direct abutment with the stop 35 of the housing 12.

It is obvious from the foregoing that the linkage mechanism locks automatically when the link assembly is depressed to the maximum since the bearing center at 15 is disposed inwardly of a line drawn through the center of bearings 11 and 18. Greatest pressure is exerted by the linkage when bearings 11, 15 and 18 are in line, so when bearing 15 is raised above the center line, pressure begins to diminish, thus, the mechanism is automatically locked.

Conventional methods and their applications involved in the construction of this invention include serrated jaws adaptable to parallel engagement, a knurled adjusting head, and Acme or similar thrust bearing bolt threads.

In a modified form, which is not illustrated in the accompanying drawings, the jaw extension 20 is threaded externally for longitudinal adjustment by an internally threaded adjusting head. The remaining elements are substantially as illustrated and described.

Manifestly, the construction as shown and described is capable of further modification and such modification as may be construed to fall within the scope and meaning of the appended claims is also considered to be within the spirit and intent of the invention.

What is claimed is:

1. A sliding jaw wrench including an elongated, open ended housing having a longitudinal opening in its front, a handle pivoted intermediate its ends in one end of said housing and having an extension of reduced thickness terminating at the approximate midsection of said housing opening, an outer jaw having a longitudinally bored shank slideable in the opposite end of said housing, a bolt threaded into the bore of said shank having a head retained in slots in said housing against other than rotative movement and adapted to actuate said jaw longitudinally, an inner jaw cooperating with said outer jaw and also having a shank slideable in said housing, toggle links pivotally joining the extension of said handle and the shank of said inner jaw and adapted to yield to movement of said handle extension in said opening when said handle is actuated, the pivotal connection between said links and handle extension being disposed inwardly of a line through the centers of the pivots on opposite sides of said pivotal connection to lock said extension,

links and inner jaw shank in axial alignment and means for securing said handle against pivotal displacement with respect to said housing.

2. A sliding jaw wrench including an elongated housing having open ends and opposed slots in the sides thereof, an outer jaw having a shank slideable in one end of said housing, an adjusting head disposed in the slots of said housing and constrained thereby against other than rotative movement, said adjusting head having threaded engagement with said outer jaw shank to effect longitudinal sliding displacement thereof, an inner jaw cooperating slidably with said outer jaw and having a shank also slideable in said housing, a handle pivoted in the opposite end of said housing and having an extension entering said housing, toggle links pivoted at their upper ends to said inner jaw shank and at their lower ends to said handle extension in offset relationship with the pivots of said handle and the upper ends of said links, to lock said handle extension, toggle links and inner jaw shank in axial alignment when said handle is moved in one direction to move said inner jaw towards said outer jaw.

3. A sliding jaw wrench including a housing having an elongated opening in one side thereof, an outer and an inner work engaging jaw, each having a shank slideable longitudinally in one end of said housing, means held against other than rotative movement in slots in said housing for longitudinally adjusting said outer jaw, a handle pivoted in the opposite end of said housing and having an extension in said housing, a pair of parallel links pivotally attached to said handle extension at their lower ends and to the shank of said inner jaw at their upper ends and biasing said handle extension to outward displacement in said housing opening to effect limited retractive movement of said inner jaw with respect to said outer jaw.
